UNITED STATES PATENT OFFICE.

JOSEPH HERBERT CHASE, OF NEW YORK, N. Y., ASSIGNOR TO AMERICAN PIANO COMPANY, OF NEW YORK, N. Y., A CORPORATION OF NEW JERSEY.

AUTOMATIC TRACKING DEVICE.

Application filed June 6, 1916, Serial No. 101,884. Renewed August 8, 1921. Serial No. 490,810.

To all whom it may concern:

Be it known that I, JOSEPH HERBERT CHASE, a citizen of the United States, residing in the city of New York, in the county 5 of New York, State of New York, have invented an Improvement in Automatic Tracking Devices, of which the following is a specification.

This invention relates to improvements in 10 automatic or semi-automatic player pianos in which a perforated note sheet is passed over a tracker bar having a series of apertures therein, so that the perforations in the note sheet upon registering with the apertures 15 in the tracker bar cause the sounding of notes in proper sequence by piano player mechanism. The invention relates particularly to means for securing the proper registration of the perforations in the note 20 sheet with the apertures in the tracker bar, such mechanism being commonly termed a tracking device.

For purposes of illustration and description a preferred embodiment of the invention 25 is shown in the accompanying drawings and therein;

Figure 1 shows diagrammatically and substantially in vertical longitudinal section, a mechanism constructed in accordance with the present invention by which proper alignment or lateral adjustment between note sheet and tracker bar may be automatically secured; and

Figure 2 is a section on the line 2—2 of 35 Figure 1, on reduced scale.

Referring to the drawings which show an ordinary spool box such as is commonly found in player pianos, a removable note sheet spool 1 is mounted between a spring 40 pressed bearing 2 and a longitudinally slideable bearing 3 journaled respectively in the left and right hand walls of the spool box. The left hand bearing 2 comprises a shaft 4 journaled in a suitable manner and normally pressed to the right by a spring 5. The right hand bearing comprises a shaft 6 suitably journaled in the wall of the spool box and having means to engage the flange of the music sheet spool which may be inserted 45 between the bearings. The shaft 6 has a collar 7 to limit its movement to the right and a collar 8 to limit its movement to the left. Integral with the shaft 6 is a pinion 9 through which the spool may be driven

in rewinding the music sheet thereon. A 55 take-up roll 10 is also suitably journaled in the spool box and is provided with a gear 11 by which it may be rotated to cause a note sheet 12 to be wound thereon during the operation of the instrument. 60

The means herein shown for securing the proper alignment of the music sheet as it passes over a tracker bar 13 comprises mechanism operable by the edge of the music sheet and pneumatic means for adjusting 65 the note sheet laterally of the tracker bar. For the purpose of simplifying the tracking device, means are shown for moving only the note sheet spool; the same being herein shown as a bellows 14 having an arm 15 70 connected to its movable board and a rod 16 pivoted to the arm 15. The rod 16 bears against the upper end of a lever 17 fulcrumed at 18 and bearing against the right hand end of the shaft 6 at 19. It will be 75 apparent that as the pneumatic 14 is collapsed more or less the shaft 6 and the note sheet spool will be moved to the left, and that as the pneumatic 14 is allowed to expand the note sheet spool will move to the 80 right under the action of the spring 5.

Means are herein provided for collapsing the pneumatic 14 more or less, the said means being governed by the position of the left hand edge of the note sheet. The bellows controlling means will be next described.

Mounted in the left hand wall of the spool box is a valve mechanism 20 adapted by its action under the guidance of the edge of the 90 note sheet to control a port located in a connection between bellows 14 and a source of exhaust. This valve is preferably of cylindrical construction and has a disc 21 mounted upon a shaft 22. The shaft 22 of the 95 valve carries two pistons 23 and 24 one of said pistons controlling a port 25 in the cylindrical valve casing 26 and the other piston performing a function which will be later described. The port 25 opens into a 100 duct 27 leading from the interior of the valve to the pneumatic 14. A duct 28 opening through a port 29 to the interior of the valve leads to a source of exhaust. It will thus be apparent that rarefied air will be 105 present in the chamber formed at the left of the piston 23. A port 30 admits atmospheric air to the right of the piston 23.

Thus if the piston 23 is moved to the right to place duct 27 in communication with duct 28 air will be exhausted from bellows 14 and through the train of mechanism previously 5 described will move the music sheet spool to the left. Similarly if the piston 23 is moved to the left it will place duct 27 in communication with the atmosphere and allow the bellows 14 to expand under the action of 10 spring 5, thereby permitting the music sheet spool to move to the right.

In operation it is desired that the piston 23 be controlled in its position by the edge of the music sheet and for this purpose it is 15 essential that the disc 21 be caused to bear against the edge of the music sheet lightly without undue tendency to tear or fray the edge of the paper. The means herein provided to insure a light bearing of the disc 21 20 against the edge of the paper are shown as operating pneumatically. In other words, pneumatic pressure causing the disc to bear against the edge of the sheet is employed instead of the usual spring pressure or that 25 pressure provided by a weight and lever.

To the left of the piston 24 is a port 31 by which atmospheric air will be admitted to the left of the piston 24. The diameter of the piston 24 and the interior diameter of 30 the cylinder adjacent this piston are slightly greater than the diameter of the piston 23 and the interior diameter of the cylinder adjacent thereto. It will therefore be apparent that the pneumatic force 35 tending to move the valve, (the air being exhausted from the chamber formed between the pistons) will be the differential between exhaust pressure acting upon the inner faces of the pistons and atmospheric pressure acting upon the outer faces of the pistons. As 40 the faces of the piston 24 are of greater area than those of piston 23 there will be a tendency to move the valve to the right and therefore the disc 21 will bear lightly against 45 the edge of the paper during the operation of the apparatus. As the duct 28 is preferably disconnected from the source of exhaust during the rewinding of the note sheet, during rewinding the disc 21 will not bear 50 against the edge of the paper, and if it contacts therewith at all it may be pushed to the left and thereafter will not engage the edge of the paper.

In operation the note sheet is inserted in 55 the instrument in the ordinary way and is attached to the take-up roll by suitable means. The note sheet thus lies across the tracker bar and in the path of movement of the disc 21. The note sheet spool and the 60 note sheet will be initially out of proper alignment, being held to the right by the spring 5 so that the collar 7 bears against the journal bearing at the left of the spool box. In this position the bellows 14 is ex- 65 panded to its full extent. If now the ex-

hausting apparatus is started, the air in the chamber formed between the two pistons will be partially exhausted through the duct 28. This will cause the disc 21 to be moved to the right against the edge of the note 70 sheet. This movement to the right places the duct 27 in connection with the duct 28 and thereby exhausts air from bellows 14. The collapsing of the bellows due to the exhaust of air moves the note sheet spool and 75 the note sheet to the left. The edge of the paper bearing against the disc 21 is likewise moved to the left and moving the piston 23, closes or partially closes port 25. Such primary adjustments may be made that when 80 the music sheet is in proper alignment with the tracker bar the bellows 14 will be substantially half collapsed. Therefore as the note sheet moves to the left in response to the collapse of the bellows 14 the piston 23 will 85 substantially close port 25 when the bellows is about half collapsed and the note sheet in proper alignment. In any event the piston 23 will so position itself relatively to the port 25 as to maintain the bellows 14 in 90 about half collapsed condition and the exhaust of air from the bellows 14 through the port 25 will be just sufficient to make up for the leakage of atmospheric air thereto.

The note sheet having thus been carefully 95 positioned at the start of the operation of the apparatus the manner in which the correct alignment is maintained throughout the playing of a composition will next be described.

The piston 23 is of substantially the same width as the port 25. If now the note sheet for some reason or other wanders to the left out of proper alignment, the control valve and the piston 23 will also move to the left. 105 This will cause the opening of port 25 to the atmosphere. Atmospheric air being thus admitted to the bellows 14 the same will expand under the action of spring 5 and the music roll will be moved to the right into 110 proper alignment; the disc 21 following the edge of the sheet and cutting off the admission of atmospheric air through port 25 slightly prior to the assumption of the correct position by the note sheet. 115

Again if the note sheet wanders to the right out of proper alignment, the valve carrying the piston 23 will also move to the right and will open or enlarge the opening of the port 25 to exhaust. The bellows 14 120 being still further exhausted causes the same to collapse and the music sheet spool is moved to the left, thereby restoring the note sheet to proper alignment with the tracker bar. 125

It has been noted heretofore that means are provided whereby the tendency to fray or tear the edge of the note sheet will be minimized. Means for this purpose are herein provided for as follows: The valve 130

member with its two pistons and circular disc 21 is freely rotatable within its cylindrical casing. Preferably the valve is so mounted that its axis of rotation will lie 5 without the plane of the perforated note sheet while bearing against a portion of the disc outside its axis of rotation and thereby tending to rotate the disc. This not only minimizes the wear upon the paper but 10 also permits a torn portion of the edge of a note sheet to ride up upon the edge of the disc and in this way be not further torn thereby.

The operation of a tracking device such as 15 herein described is greatly facilitated if the note sheet is correctly wound upon the note sheet spool. In the specific embodiment of this invention herein shown the operation of the tracking device is such that the note 20 sheet will be correctly and evenly wound upon the take-up roll. Therefore if some means are provided to operate during the re-winding of the note sheet onto the note sheet spool, the subsequent correct tracking 25 of the note sheet when it is again inserted in the instrument will be greatly facilitated.

It is desirable in this specific embodiment of the invention that the note sheet spool be 30 freely movable during the playing of a composition in order that correct lateral adjustment may be secured at all times between the note sheet and tracker bar. Such being the case, the note sheet spool will be out of 35 proper alignment when the tracking device is inactive (the spool being forced to the right by the spring 5) and if the note sheet is then rewound it may bind against a flange of the spool and be unevenly rewound thereon. If the note sheet spool is positioned in 40 correct alignment with the take-up roll, during the rewinding of the note sheet, the note sheet may be evenly rewound.

Means are herein provided for accomplishing the desired results above noted and 45 the same is shown as mechanism to correctly position the note sheet spool during rewinding, and operatively connected to the rewind lever. Pivoted at 32 above is a lever 33. A link 34 connects the lever 33 to a 50 conventional rewind control lever 35. With the parts in the position shown the instrument is in condition for playing and the note sheet, during the playing of the instrument, is kept in correct alignment by the 55 mechanism previously described. Upon rewinding the note sheet it is customary to cut off the exhaust from the ducts leading to the tracker bar and preferably the tracking device previously described is also thrown out 60 of operation; it being undesirable to have any part contacting with the edge of the note sheet during the comparatively fast re-

winding operation. If, therefore, the rewind control lever 35 is moved to the right, the lever 33 will be rotated in a counter-clockwise direction about its pivot and will contact with the lever 17 below its fulcrum 18. When properly adjusted this will hold the note sheet spool approximately in the position shown in the drawings which is 65 substantially in alignment with the take-up roll. This will assure the proper rewinding 70 of the note sheet.

It is to be understood that the present invention may be variously modified and embodied within the scope of subjoined claims. 75

I claim as my invention:

1. An automatic tracking mechanism for player pianos comprising, in combination, a bellows having a single port, the said port 80 opening to an exhaust means; means operatively connected to the movable board of said bellows for effecting relative lateral adjustment of a note sheet spool and tracker bar; and a single valve interposed between 85 said bellows and the exhausting means including a member bearing directly against an edge of the travelling note sheet thereby to control directly the flow of air from said bellows to secure proper relative lateral adjustment of note sheet spool and tracker bar. 90

2. In a player piano, the combination of a tracker bar; means to pass a perforated note 95 sheet over said tracker bar; a note sheet spool; a take-up roll; means acting upon said note sheet spool and operative during the playing of the instrument to secure correct lateral adjustment of the note sheet and the tracker bar; and means manually controlled independently of the note sheet to align the note sheet spool with the take-up roll during rewinding to cause the note sheet to be rewound in correct alignment upon the note sheet spool. 100

3. In a player piano the combination of an endwise adjustable music sheet spool, a tracker bar having a series of apertures therein; a note sheet having perforations to register with the apertures in the tracker 110 bar; means including a take-up roll for passing the note sheet over the tracker bar; means operative during the playing of the instrument to laterally adjust the note sheet in proper alignment with the tracker bar 115 and take-up roll; a rewind lever; and further means connected with the rewind lever to align the note sheet spool and take-up roll during rewinding of the note sheet.

In testimony whereof, I have signed my 120 name to this specification this 3rd day of June, 1916.

J. HERBERT CHASE.
